(57) **CLAIM**

The ornamental design for a signature light arrangement for a taillight, as shown and described.

DESCRIPTION

FIG. 1 is a front left perspective view of a signature light arrangement for a taillight according to the present invention.

FIG. 2 is a front view of the signature light arrangement shown in FIG. 1.

FIG. 3 is a left side view thereof.

FIG. 4 is another front view thereof shown in use; and, FIG. 5 is a front view mirror image thereof shown in use. In FIGS. 1-5, for visual clarity, a darker shade located within the enclosed broken lines is used to show the activated state of the signature light arrangement, in inverted fashion. In FIGS. 1-3 the surrounding lighter tone portions, or de-emphasized portions, located outside of the enclosed broken lines are included for environmental purposes, and form no part of the claimed design. In FIGS. 4 and 5, the surrounding broken lines that show the rest of a vehicle, located outside of the enclosed broken lines are included for environmental purposes and form no part of the claimed design.
